DISPLAY CONTAINER

Edgard Feder, New York, N.Y.

Application May 31, 1951, Serial No. 229,223

10 Claims. (Cl. 206—45.13)

1

This invention relates to display containers. It is an object of the present invention to provide a display container having a display platform which is movable from a hidden position when the container is closed to an exposed position when the container is opened.

It is another object of the present invention to provide a display container of the character described which is self-locking in open position.

It is another object of the present invention to provide a display container of the character described which may be simply manufactured from light and inexpensive materials.

It is another object of the present invention to provide a display container of the character described which is sturdy and durable.

It is another object of the present invention to provide a display container of the character described which is novel in construction whereby the foregoing objects are accomplished.

Other objects of the invention will in part be obvious and in part will be pointed out hereinafter.

The invention accordingly consists in the features of construction, combinations of elements and arrangements of parts which will be exemplified in the device hereinafter described and of which the scope of application will be indicated in the appended claims.

In the accompanying drawings in which is shown one of the various possible embodiments of the invention,

Fig. 1 is a perspective view of a closed display container constructed in accordance with the present invention, the container being partially cut away to show the internal construction;

Fig. 2 is a perspective view to a reduced scale of the container shown in Fig. 1, the same being illustrated in open position;

Fig. 3 is an enlarged sectional view taken substantially along the line 3—3 of Fig. 1;

Fig. 4 is a sectional view taken substantially along the line 4—4 of Fig. 3; and

Fig. 5 is a view similar to Fig. 3 but showing the container in open position.

Referring now in detail to the drawings, the reference numeral 10 denotes a casing of a display container 12, fabricated, e. g., from sturdy material such as cardboard or thin panels of wood. Said casing comprises an open-top box having side walls 14, 16, a bottom wall 18 and end walls 20. Although the box is shown as having a rectangular plan configuration, it is to be understood that the invention is not to be limited thereby and that alternative suitable plan con-

2

figurations may be employed, such as, for example, configurations with rounded ends.

A display platform 24 is located in the casing and in the closed position of the container is disposed almost at the bottom thereof. Said platform desirably has a contour matching the plan contour of the box, i. e. is rectangular in shape, preferably being slightly less in size than the bottom panel, and for best results it is semi-snugly slidable in the casing.

Means is included on said platform to secure objects to it, the means shown in the drawings being a string 26.

The platform is employed to support articles to be displayed, and the present invention is concerned primarily with providing means to raise the platform to the top of the casing whereby objects on it are viewable, and with providing means to automatically lock the platform in raised position until it is manually unlocked permitting lowering of the platform.

Pursuant to the present invention, a pair of rectangular panels 28 as long as the container and half as wide is provided, each panel being hinged by a flexible strip 29 to the top edge of a different side wall. A narrow rectangular panel 30 as long as the panels 28 is secured as by cementing on the top surface of each said panel 28 at its outer long edge, i. e. its edge remote from the hinge, the outer edge of each panel 30 being registered with that of its associated panel 28.

A rectangular panel 32 is hinged by a flexible strip 31 to the inner long edge of each panel 30, each pair of panels 30, 32 being thus adapted to lie in a common horizontal plane immediately above the panel 28 when the container is closed (see Fig. 3). Preferably the panels 30, 32 are secured to the strip 31 in slightly spaced apart relationship to permit relative translatory as well as pivotal movement. The combined width of each pair of panels 30, 32 is equal to or slightly less than the width of a panel 28. Each panel 32 is as long as a panel 30. Thus, a pair of panels 30, 32 cover the entire top surface of a panel 28.

A rectangular panel 34 as long as a panel 32 and somewhat narrower is secured as by cementing to the top surface of each panel 32, the outer edge of the panel 34 being registered with the corresponding edge of its associated panel 32. To the top surface of each panel 34 is secured, as by cementing, a rectangular panel 36 equal in size to a panel 28 and having its outer edge registered with the corresponding edge of its as-

3

sociated panel 34 whereby the two panels 36 can completely close the casing. A notch 35 is thereby produced between the facing surface of panels 30, 36.

It will be observed that in accordance with the foregoing construction the cover for the casing constitutes two halves, each of which includes two units. The first of these units comprises the panels 28, 30 and the second, which has the notch 35 at its inner longitudinal edges, comprises the panels 32, 34, 36. The first unit is hinged to the casing, and the second unit is hinged to the first.

A flexible ribbon 38 made, for instance of cloth runs under each end of the platform near the end walls of the casing, each ribbon being secured as by cementing to the bottom of the platform. The ends of each ribbon are attached as by cementing under the outer edges of the panels 32 near the ends thereof. Each hinge strip 29 stops short of the ends of its associated panel 28 so that clear spaces are provided between the panels 28, 32 through which the ribbons can slide.

In the form of the invention illustrated the length of each ribbon is such that when the platform is adjacent the bottom wall of the casing, the ribbon will have no slack therein. To this end the combined widths of the panels 28, 34 is approximately equal to the height of the casing above the platform when the container is closed, and the length of ribbon between the top of the casing and the bottom of the platform is substantially equal to the depth of the casing.

If the height of the casing above the platform is appreciably greater than the combined widths of the panels 28, 34, the platform will be suspended above the bottom wall of the casing when the container is closed, or the platform, if the ribbon is lengthened to prevent such suspension, will be below the top of the casing when the container is open. If the combined widths of the panels 28, 34 appreciably exceeds the height of the casing above the platform, there will be slack in the ribbons when the container is closed.

It will be observed that in no case should the length of the ribbon from the top of the platform to the top of the closed container be less than the combined width of the panels 28, 34.

A tab 40 is secured to the middle of the outer edge of each panel 32.

To raise the platform and automatically lock the same in raised position the tabs simply are pulled outwardly as far as they will go and are released. The sequence of operation consequent upon such manipulation is as follows:

As the tabs initially are pulled, each panel 28 will turn on its hinge 29 to a vertical position and each panel 32 will then pivot outwardly on its hinge until it reaches a position 180° from that at which it started. At the same time, each panel 28 will continue to move from its original position until abutted by an associated panel 36 carried by an associated panel 32 by means of an associated panel 34. At this point each panel 28 will lie in the same plane as its associated panel 34, and the facing edges of these panels will be separated by a distance equal to the sum of the width of a panel 32 and the width of a hinge strip 31 minus the sum of the widths of a panel 30 and a panel 34. At this point each panel 36 extends over the adjacent edges of its associated panels 28 and 34, and panel 32 lies under both adjacent edges, it lying directly un-

der the panel 34 and under panel 30 which is attached to panel 28, the panel 30 lying below panel 28 at this point. Thus, a cavity 52 is produced from the notch, said cavity being located between associated panels 32 and 36. The weight of the tray will pull panel 34 towards panel 28 thereby forcing the latter into the cavity. Panel 32 will be able to slide along panel 30 because the hinge strip 31 therebetween is flexible and of a width as specified above. The display case is now locked in open position as the panel 28 cannot move about its associated hinge strip 31 until its associated panel 34 is manually pulled away from it to free its associated panel 30 because panels 28 and 30 are held between the associated panels 32 and 36. The ribbon on complete opening will have been pulled upwardly a distance equal to the combined widths of associated panels 28 and 34 whereby the tray has been brought into view.

It should be noted that associated panels 30, 32 must be close enough together where attached by a hinge strip 31 so that panel 30 cannot fail to enter the notch when the cover is opened.

It thus will be seen that there is provided a device which achieves all the objects of the invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described the invention, there is claimed as new and desired to be secured by Letters Patent:

1. A display container comprising an open-top casing, a platform disposed in said casing, a two-part cover for said casing, each said part including a first and a second unit, means to hinge the first of said units to a side of the casing, means to hinge the second unit to the first unit remote from the first-named hinging means, said second unit having a notch extending along an edge thereof parallel to the edge of the casing to which the first unit is hinged, said notch being disposed to receive an edge of the first unit when the cover part is opened, at least one flexible elongated member connected to one side of the platform and having an end connected to the second unit of one of the cover parts remote from the second-named hinging means, and a flexible elongated element connected to the other side of the platform and having an end connected to the second unit of the other cover part remote from the second-named hinging means, whereby when said cover parts are opened the platform will be raised bodily and will be automatically locked in raised position.

2. A display container comprising an open-top casing, a platform disposed in said casing, a two-part cover for said casing, each said part including a first and a second unit, means to hinge the first of said units to a side of the casing, the second of said units having a longitudinally extending notch in an edge thereof, means to hinge the first unit to the second unit remote from the first-named hinging means and at a side of the notch whereby an edge of the first unit is adapted to enter the notch when the two units are swung relative to one another, at least one flexible elongated element connected to one side of the platform and having an end connected to the second

unit of one of the cover parts remote from the second-named hinging means, and a flexible elongated element connected to the other side of the platform and having an end connected to the second unit of the other cover part remote from the second-named hinging means, whereby when said cover parts are opened the platform will be raised bodily and will be automatically locked in raised position.

3. A display container comprising an open-top casing, a platform disposed in said casing, a two-part cover for said casing, each said part including a first and a second unit, means to hinge the first of said units to a side of the casing, the second of said units having a longitudinally extending notch in an edge thereof, means to loosely hinge the first unit to the second unit remote from the first-named hinging means and at a side of the notch whereby an edge of the first unit is adapted to enter the notch when the two units are swung relative to one another, at least one flexible elongated element connected to one side of the platform and having an end connected to the second unit of one of the cover parts remote from the second-named hinging means, and a flexible elongated element connected to the other side of the platform and having an end connected to the second unit of the other cover part remote from the second-named hinging means, whereby when said cover parts are opened the platform will be raised bodily and will be automatically locked in raised position.

4. A display container comprising an open-top casing, a platform disposed in said casing, a two-part cover for said casing, each said part including a first and a second unit, means to hinge the first of said units to a side of the casing, the second of said units having a longitudinally extending notch in an edge thereof, means to loosely hinge the first unit to the second unit remote from the first-named hinging means and at a side of the notch whereby an edge of the first unit is adapted to enter the notch when the two units are swung relative to one another, the opposite side of the notch overhanging the side of the notch on which the hinge is located, at least one flexible elongated element connected to one side of the platform and having an end connected to the second unit of one of the cover parts remote from the second-named hinging means, and a flexible elongated element connected to the other side of the platform and having an end connected to the second unit of the other cover part remote from the second-named hinging means, whereby when said cover parts are opened the platform will be raised bodily and will be automatically locked in raised position.

5. A display container comprising an open-top casing, a platform disposed in said casing, a two-part cover for said casing, each said part including a first and a second unit, means to hinge the first of said units to a side of the casing, the second of said units having a longitudinally extending notch in an edge thereof, means to loosely hinge the first unit to the second unit remote from the first-named hinging means and at a side of the notch whereby an edge of the first unit is adapted to enter the notch when the two units are swung relative to one another, the opposite side of the notch overhanging the side of the notch on which the hinge is located, at least one flexible elongated element connected to one side of the platform and having an end connected to the second unit of one of the cover parts at an edge remote from the notch thereof, and a flexible

elongated element connected to the other side of the platform and having an end connected to the edge remote from the notch thereof, whereby when said cover parts are opened the platform will be raised bodily and will be automatically locked in raised position.

6. A display container comprising an open-top casing, a platform disposed in said casing, a two-part cover for said casing, each said part including a first and a second unit, means to hinge the first of said units to a side of the casing, the second of said units having a longitudinally extending notch in an edge thereof, means to loosely hinge the first unit to the second unit remote from the first-named hinging means and at a side of the notch whereby an edge of the first unit is adapted to enter the notch when the two units are swung relative to one another, the opposite side of the notch overhanging the side of the notch on which the hinge is located, at least one flexible elongated element connected to one side of the platform and having an end connected to the second unit of one of the cover parts remote from the second-named hinging means, and a flexible elongated element connected to the other side of the platform and having an end connected to the second unit of the other cover part remote from the second-named hinging means, whereby when said cover parts are opened the platform will be raised bodily and will be automatically locked in raised position, the length of each flexible element from the top of the platform to its point of connection to the second unit being substantially equal to the distance from the top of the platform to the top of the casing.

7. A display container comprising an open top casing, a platform disposed in said casing, a two part cover for said casing, each said part including a first and a second unit, means to hinge the first of said units to a side of the casing, mounting means remote from the hinging means, said last-named means mounting the second unit on the first unit for extension therefrom, means for automatically locking the second unit in extended position, at least one flexible elongated member connected to one side of the platform and having an end connected to the second unit of one of the cover parts remote from the mounting means, and a flexible elongated element connected to the other side of the platform and having an end connected to the second unit of the other cover part remote from the mounting means, whereby when said cover parts are opened the platform will be raised bodily and will be automatically locked in raised position.

8. A display container comprising an open top casing, a platform disposed in said casing, a two part cover for said casing, each said part including a first and a second unit, means to hinge the first of said units to a side of the casing, means to hinge the second unit to the first unit remote from the first-named hinging means whereby the second unit can be extended from the first unit, means for automatically locking the second unit in extended position, at least one flexible elongated member connected to one side of the platform and having an end connected to the second unit of one of the cover parts remote from the second-named hinging means, and a flexible elongated element connected to the other side of the platform and having an end connected to the second unit of the other cover part remote from the second-named hinging means, whereby when said cover parts are opened the

platform will be raised bodily and will be automatically locked in raised position.

9. In combination in a display container an open top casing, a platform disposed in said casing, a cover part for said casing, said cover part including a first and a second unit, means to hinge the first unit to a side of the casing, mounting means remote from said hinging means, said last-named means mounting the second unit on the first unit for extension therefrom, means for automatically locking the second unit in extended position, and at least one flexible elongated member connected to one side of the platform and having an end connected to the second unit of the cover part remote from the mounting means.

10. In combination in a display container an open top casing, a platform disposed in said casing, a cover part for said casing, said cover part including a first and a second unit, means to hinge the first of said units to a side of the casing, means to hinge the second unit to the first unit remote from the hinging means of the first

unit to the casing whereby the second unit can be extended from the first unit, means for automatically locking the second unit in extended position, and at least one flexible elongated member connected to one side of the platform and having an end connected to the second unit of the cover part remote from the second-named hinging means.

EDGARD FEDER.
